UNITED STATES PATENT OFFICE.

JOSEPH T. SCHLACKS, OF DETROIT, MICHIGAN, ASSIGNOR TO McCORD MANUFACTURING COMPANY, OF DETROIT, MICHIGAN, A CORPORATION OF MAINE.

CELLULAR RADIATOR.

1,318,012.

Specification of Letters Patent.

Patented Oct. 7, 1919.

Application filed September 19, 1914. Serial No. 862,440.

To all whom it may concern:

Be it known that I, JOSEPH T. SCHLACKS, a citizen of the United States, residing at Detroit, in the county of Wayne and State 5 of Michigan, have invented certain new and useful Improvements in Cellular Radiators; and I do hereby declare the following to be a full, clear, and exact description of the invention, such as will enable others skilled 10 in the art to which it appertains to make and use the same.

My invention relates to radiators of the type used in automobiles, and more generally in connection with explosive engines, 15 and is particularly directed to the improvement of cellular radiators. Generally stated, the invention consists of the novel construction and combination of parts hereinafter described and defined in the claims.

20 The radiator in its preferred form, is illustrated in the accompanying drawings, wherein like characters indicate like parts throughout the several views.

25 Referring to the drawings: Figure 1 is a diagrammatic view in front elevation showing a radiator designed in accordance with my invention;

Fig. 2 is a perspective view with some parts broken away and some parts sectioned, 30 showing the cellular structure of the radiator core;

Fig. 3 is a perspective view showing one of the zigzag water tubes of the radiator;

Figs. 4 and 5 are perspective views showing 35 intermediate cell forming plates of the radiator core;

Fig. 6 is a horizontal section taken approximately on the line $x^6 x^6$ on Fig. 2; some parts being broken away;

40 Fig. 7 is a view partly in front elevation and partly in vertical section showing two of the zigzag water tubes and two intermediate cell forming plates of the radiator, the said parts being separated; and

45 Fig. 8 is a view corresponding to Fig. 7, but showing the several elements assembled and operatively connected.

In Fig. 1, the radiator frame is indicated by the numeral 1, the upper water chamber 50 of the radiator by the numeral 2, and the lower water chamber of the radiator by the numeral 3.

The cellular core structure of the radiator is made up of a plurality of thin sheet metal 55 (preferably of brass) plates that are bent

into zigzag form and certain of which are adapted to be assembled in parallel to form zigzag water tubes, and certain others of which are located intermediate of the water tubes and coöperate with the plates of the 60 water tubes and with each other to afford horizontal air cells or passages opening at the front and rear ends. The zigzag tube forming plates are indicated by the numeral 4, while the zigzag intermediate plates are 65 indicated by the numeral 5. In vertical cross section, the plates 4 and 5 follow like zigzag lines, and in the preferred construction they are successively bent to form the three 70 sides of hexagonal cells. The tube forming plates 4, at their front and rear edges are offset at 4^a, so that they are brought closely together, and these joints are connected by solder so that the tubes are closed at front and rear, but are left open at top and bottom 75 for communication with slots 6 in the bottom plate of the upper water chamber 2, and with like slots, not shown, in the top plate of the lower water chamber 3. In the preferred arrangement of this radiator, two 80 intermediate plates 5 are placed between each pair of adjacent zigzag water tubes, and each intermediate plate 5 has a flat surface 5^a that has an extended flat contact with a corresponding flat vertical portion 4^b of 85 the adjacent plate 4 of the adjacent water tube. This extended contact insures good conduction of heat from the plates of the water tube into the intermediate plates, so that the said intermediate plates afford 90 highly efficient radiating surfaces for the water tubes. It should be further noted that the said surfaces 5^a, at their ends, are offset, as indicated at 5^b, so as to closely engage the offset edge portions 4^a of the tube 95 forming plates 4. The two intermediate plates 5 also have flat vertically extended co-engaging surfaces 5^c. The intermediate plates 5, therefore, coöperate with each other and with the adjacent tube forming 100 plates 4, to afford hexagonal horizontally extended air cells or passages that are open both at front and rear ends.

The proper alinement of the plates 4 and 105 5 to form the hexagonal cells, as above described, is insured by providing the intermediate plates 5 with reversely bulged alining portions 7, certain of which fit the re-entrant bends or angles of the adjacent plates. This construction is well illustrated 110

in Figs. 4, 5, 7 and 8, by reference to which it will be noted that the said reversely bent portions 7 are simply pressed from the sheet in a direction reverse to the direction of the 5 main portion of the angular channel from which it is partly cut and laterally pressed. These alining portions 7, therefore, so closely fit the walls of the reentrant bends of the plates which they engage, that they 10 almost disappear from view, but nevertheless, afford simple and efficient means for accurately directing the assembling of the plates, and, in the completed structure, very greatly increase the conducting contact between 15 connected plates. They add practically nothing to the cost of forming the plates and do not obstruct the free passage through the air cells.

To provide for vertical circulation of air 20 between the air cells as well as horizontal circulation of air therethrough, the non-contacting portions of the intermediate plates 5 are formed with perforations 8.

When the parts of the radiator core are 25 assembled, as above described, all of the contacting portions at the front and rear edges of the plates are connected by solder, preferably accomplished by dipping the edges of the plates into molten solder. In 30 this radiator the number of joints which must necessarily be soldered liquid tight, is reduced to a minimum, and a maximum number of air cells is obtained, with the resulting greatest possible radiating and water 35 cooling efficiency. The accurate assemblage of the coöperating elements is made an easy matter, and the completed radiator core is not only comparatively strong, but has the very much desired hexagonal or honeycomb 40 cell appearance. The metallic plates or ribbons from which the cellular core is made are of the simplest possible construction capable of being very easily pressed to form and not requiring plaiting or folding 45 of the metal back upon itself in an intricate or difficult manner. Furthermore, the interchangeable construction of the zigzag plates or ribbons permits of variation in the manner of assembling, so that one, two, 50 three or more intermediate or radiating plates may be assembled between adjacent laterally spaced zigzag water tubes.

Also, the said construction, above described, permits the water tubes to be directly 55 connected together, without intermediate radiating plates, when such construction is desired.

What I claim is:

1. A radiator made up of sheet-metal 60 plates successively bent to form the three sides of alternated hexagonal cells and connected in parallel to form spaced zigzag water tubes, and alining means located between the tubes and fitting the hexagonal 65 channels of adjacent plates.

2. A cellular radiator made up of alternately bent zigzag plates, certain of which are united in parallel to form laterally spaced water tubes, and certain others of which are assembled between said water 70 tubes and coöperate with the adjacent plates thereof to form air cells, and are provided with reversely bent alining portions that fit the reentrant bends of the adjacent tube forming plates. 75

3. A cellular radiator made up of alternately bent zigzag plates, certain of which are united in parallel to form laterally spaced water tubes, and certain others of which are assembled between each pair of 80 the said tubes and coöperate with the adjacent plates thereof and with each other to form air cells, the said intermediate plates having reversely bent alining portions that fit the reentrant bends of adjacent plates. 85

4. A cellular radiator made up of sheet metal plates successively bent to form the three sides of hexagonal cells, certain of the said plates being connected in parallel to form laterally spaced zigzag water tubes, 90 and certain others of the said plates being assembled between said water tubes and coöperating with the adjacent plates thereof to form hexagonal air cells, the said intermediate plates having reversely bent alining 95 portions fitting the reentrant angles of said tube forming plates.

5. A cellular radiator made up of sheet metal plates successively bent to form the three sides of hexagonal cells, certain of the said plates being connected in parallel to form laterally spaced zigzag water tubes, and certain others of the said plates being assembled between said water tubes and coöperating with the adjacent plates thereof to 100 form hexagonal air cells, the said intermediate plates having reversely bent alining portions fitting the reentrant angles of said tube forming plates, the said parallel tube forming plates having their edges off-set 105 and directly united.

6. A cellular radiator made up of sheet metal plates successively bent to form the three sides of hexagonal cells, certain of the said plates being connected in parallel to 110 form laterally spaced zigzag water tubes, and certain others of the said plates being assembled between said water tubes and coöperating with the adjacent plates thereof to form hexagonal air cells, the said intermediate plates having reversely bent alining 115 portions fitting the reentrant angles of said tube forming plates, the said intermediate plates having perforations permitting vertical as well as horizontal circulation of air 120 through said air cells.

7. A cellular radiator made up of alternately bent zigzag plates, certain of which are united in parallel to form laterally spaced water tubes, and certain others of 125

- which are assembled between each pair of said tubes and coöperate with the adjacent plates thereof and with each other to form air cells, the intermediate plates having reversely bent alining portions that fit the re-entrant bends of adjacent plates, the reversely bent alining portions of said intermediate plates being disposed on both sides of said plates.
10. 8. A radiator made up of successively bent sheet metal plates, some of which are connected in parallel to form zigzag water tubes, said water tube plates and the remaining plates forming intervening air passages, said remaining plates having reversely bulged alining portions that fit portions of adjacent plates.
9. A radiator made up of successively bent sheet metal plates, some of which are connected in parallel to form zigzag water tubes, said water tube plates and the remaining plates forming intervening hexagonal air channels, said remaining plates having reversely offset alining portions that fit portions of adjacent plates.
10. A radiator core comprising a plurality of water tubes and a plurality of radiating fins arranged between the several water tubes, each of said tubes having two walls each of which is constructed of a corrugated strip of metal and each of said fins being constructed of a single corrugated
- strip of metal, and each of said fin strips being provided on its opposite sides with centering loops which are of substantially the same form in cross section as the corrugations of the water tube and fin strips and project laterally from the concave faces of its corrugations and engage with the concave faces of the corrugations of adjacent strips.
11. A radiator core comprising a plurality of water tubes, and a plurality of radiating fins, at least one of which is arranged between two adjacent water tubes, each of said tubes having two walls each of which is constructed of a strip of corrugated metal and each of said fins being constructed of a single corrugated strip of metal, and each of said fin strips being provided on its opposite sides with centering loops which are of substantially the same form in cross section as the corrugations of the water tube and fin strips and project laterally from the concave faces of its corrugations and engage with the concave faces of the corrugations of adjacent strips.

In testimony whereof I affix my signature in presence of two witnesses.

JOSEPH T. SCHLACKS.
